UNITED STATES PATENT OFFICE.

FREDERICK A. HART, OF NEW BRITAIN, CONNECTICUT, ASSIGNOR TO REMINGTON TYPEWRITER COMPANY, OF ILION, NEW YORK, A CORPORATION OF NEW YORK.

TYPEWRITING MACHINE.

Application filed January 27, 1928. Serial No. 84,068.

My invention relates to typewriting machines and it has for its principal object to provide improved means in the nature of tubulator mechanism for quickly positioning the carriage.

The invention is shown applied to a machine resembling somewhat that described in the patent to Edwin E. Barney for typewriting machine, No. 1,473,920, November 10, 1923, and another form of which is shown in the application of Edwin E. Barney for Letters Patent for typewriting machine, filed July 5, 1924, Sr. No. 724,186. Said Barney patent and application show machines especially equipped for writing the toll bills of telephone companies with great ease and dispatch. In the machine shown in the present application, unlike the machine shown in the Barney patent and application, the column of tolls is accumulated by adding mechanism and the sum total of said column is written at the bottom of the column. Most of the individual tolls are in amounts less than one dollar, so that in the column in which these amounts are written the typewriter carriage in the great majority of instances needs to be brought, to begin writing, to the letter space position for tens of cents. But the totals frequently amount to more than a dollar, so that in writing the total the carriage usually needs to be brought to the units of dollars position. As applied to this particular machine, my invention has for its specific purpose to facilitate the bringing of the carriage to this units of dollars position for the purpose of writing the total.

One form of the invention is illustrated in the accompanying drawings, all of which are more or less fragmentary in character, so as to show only as much of the machine as is necessary to an understanding of my invention.

Figure 1 is a right-hand side elevation, partly in section on the line 1—1 of Fig. 3.

Figure 2 is a fragmentary section on the line 2—2 of Fig. 3.

Figure 3 is a plan view.

Figures 4 and 5 are rear elevations, the former showing the space bar depressed and the mechanism in the resulting position, and the latter showing my tabulator key depressed and the mechanism in the resulting position.

Figure 6 is a view similar to a portion of

Fig. 4, but showing the parts after the space key has been released.

Figure 7 is a sectional view of a detail.

The machine illustrated is in its main features a Remington No. 12 typewriter, or rather it is what is now known commercially as a Remington No. 21 vertical adder, this being a No. 12 typewriter with an adding attachment capable of adding vertical columns but not including the cross footing mechanism.

The main frame of the typewriter includes a base 10, corner posts 11, and a top plate 12, the latter supporting stationary rails 13, on which by roller bearings 14 is supported a carriage truck 15. This truck supports a platen frame 16, in which is mounted a paper roller or platen 17 and on which are also mounted various paper feeding and controlling devices lettered generally 18. The usual spring drum 19 gives the carriage a tendency to travel leftward.

The machine is equipped with the usual letter and figure keys and types. The type bars operate a universal bar not shown, and from said universal bar there projects rearwardly a frame 20 mounted at its rear end on arms 21 projecting upward from a rock shaft 22, these parts vibrating toward the rear and front of the machine at each key stroke. They are connected by a link 23 with a dog rocker 24, pivoted at 25 and carrying a normally engaged stepping dog 26 and a normally disengaged fixed dog 27, constituting parts of an escapement of that type known as "ordinary," that is to say, the carriage steps on the up stroke of the key. The feed dogs engage an escapement wheel 28 mounted loosely on the rear end of a feed shaft which is journaled on a suitable frame 30. Said shaft has a back spacing wheel 31 fast thereon and connected after the ordinary manner of Remington escapement mechanism with the escapement wheel 28 by pawl and ratchet mechanism.

The carriage can be set backward one space at a time by a back spacing key (not shown) which operates a pawl, which turns the wheel 31. The escapement shaft carries at its forward end a feed pinion 32 which is adapted to engage two rack bars 33 and 34, said rack bars arranged end to end. These rack bars have a mode of operation and a construction resembling in a general way the corresponding parts described in

the Barney patent and application above referred to, but differing therefrom somewhat in detail. As best shown in Fig. 3, brackets 35 and 36 are secured to the back rail of the truck 15 by means of screws 37, and these brackets support the ends of a rod 38. A piece 40, pivoted along its forward edge on the rod 38, has its rear edge bent up to make a flange 41, to which the first rack 33 is secured by screws 42. The piece 40 is normally pressed downward to hold the rack 33 in position for engagement with the pinion 32 by means of compression springs 43 seated in holes in a cross bar 44 which is mounted at its ends in up-turned ears of the brackets 35 and 36 and secured against rotation by pins 45, Fig. 3. The downward motion of the piece 40 is limited by adjusting screws 46 screwed downward through said piece 40 and resting on the carriage rail or on a bar 47 of sheet metal which is usually present in that position in the Remington machine. The whole construction is such that the rack 33 is normally in position to cooperate with the pinion 32 as shown in Fig. 1, but it can be released by being lifted out of engagement, as shown in Figs. 4 and 5.

The second rack 34 is shorter than the rack 33 and abuts it on the right as shown. This rack is mounted on a piece 48 similar in all respects, except as to length, to the piece 40, and its downward motion is limited by screws 46. It is not necessary ever to lift this rack and it is therefore permanently held down by a set screw 50, screwed through the bar 44 as shown in Fig. 2. The two pieces 40 and 48 are held against endwise displacement along the rod 38 by means of suitable sleeves 51. As shown in Figs. 4 and 5, the racks 33 and 34 are mutilated so as to facilitate the writing of a particular form according to the general mode of operation explained in the Barney patent and application, the mutilations in the present instance differing specifically from the prior ones, however.

The program of operation contemplated includes the writing of certain matter on the left-hand part of the sheet while the carriage is under the control of the rack 33, and when this matter has been completed said rack 33 is released and the carriage is jumped until it is arrested by the engagement of the rack 34 with the feed pinion 32, as shown in Fig. 4. This is effected in the present instance, much as it is in the Barney patent and application, by means of a key or space bar 52. This bar is located, as usual in the model No. 21 Remington machine, in the keyboard, being supported by arms 53, Fig. 4, which are attached to arms 54, projecting from a rock shaft 55 which is pivoted at 56 in the base 10. Near its middle the shaft 55 has projecting therefrom an arm 57 which

through certain adjusting devices 58 carries a stud 60 articulated with an angular lever 61, pivoted at 62 and including an upwardly extending arm adapted to act on a lug 63, bent off from the link 23. The whole construction is such that the space bar operates the dog rocker 24 the same as the universal bar of the type bars. 64 is a returning spring for the lever 61 and the space bar.

According to the Barney invention an arm 65 has its forward end bifurcated to embrace the shaft 55 and it is secured to the arm 57 by means of a screw 66 so that this arm moves upward at each depression of the space bar. At its rear end the arm 65 has a push rod 67 pivoted thereto, which at its upper end is guided in the frame 30 of the escapement mechanism. The upper end of the rod 67 lies beneath a bar 68 in the nature of an angle bar, which is secured to the front face of the rack 33 by means of the same screws 42, which secure said rack bar to the flange 41. It will be noted in Fig. 3 that the bar 68 extends some distance to the right beyond the end of the rack 33 to which it is secured. The construction is such that whenever the space bar is depressed after writing the first part of a line on the bill the push rod 67 acting on the bar 68 raises the rack 33 out of engagement with the pinion 32, allowing the carriage to run to the left under the power of its spring until arrested, as shown in Fig. 4, by the first tooth of the rack 34 engaging a tooth of the pinion 32. It will be recalled that the space bar at the same time operates the ordinary carriage escapement so that on the up stroke of the space bar the carriage takes one step to the left which will bring it into the position shown in Fig. 6. This is the position for writing tens of cents in the adding column.

An electric carriage return mechanism is partially illustrated. This is not essential, but it is useful in a machine like the present, designed for very rapid work. The mechanism is fully shown and described in the patent to Frederick A. Hart dated December 29, 1925, No. 1,567,590. It includes an electric motor conventionally illustrated at 70, said motor gearing to the carriage through mechanism including a clutch. Said clutch and the motor circuit are controlled by devices at the front of the machine. A bracket 71, Fig. 3, projects forward from the front stationary rail 13 and two rods, 72 and 73, have their right-hand ends guided in said bracket, their left-hand ends being connected with the controlling mechanism for the motor. The rod 73 has an arm 74 fixed thereon and adapted to be struck by a margin stop 75 at the end of the leftward travel of the carriage. The arm 74 is thereby pushed a short distance leftward, resulting in closing the clutch and the circuit of the motor 70,

so that after striking the last printing key in a line, the carriage immediately moves back to its extreme right-hand position. During the rightward run of the carriage 5 another margin stop 76, also mounted on the front rail of the truck, strikes an arm 77 projecting from the rod 72 and moves said arm and rod rightward until the former is arrested by the bracket 71. The rod 72 when 10 thus operated checks the travel of the carriage and opens the clutch and circuit. Associated with the devices just described are certain cover plates 78 and 80 mounted on the front rail of the truck and which need 15 not be further referred to.

The adding mechanism is of the well known Remington construction. It is fully shown and described sufficiently so for the present purposes in the patent to Wahl, No. 1,270,471 dated June 25, 1918. But the present machine does not include those parts of the mechanism described in said patent whose functions have to do with cross footing, the present machine being capable only of vertical addition. The numeral keys work an actuator including a master wheel 81, Fig. 3, which master wheel operates in succession the denominational gear trains of a vertical totalizer 82, which totalizer is mounted on a truck 83, which by screws 84 is connected with certain brackets 85 secured to the end bars of the carriage truck by means including screws 86, so that the truck 83 and totalizer 82 travel right and left in unison with 25 the typewriter carriage. The actuator frame work has for its main piece a casting 87 fastened to two brackets 88 cast integrally with the top plate 12 of the typewriter. At its middle part this casting carries a pointer 90 which cooperates with graduations 91 on the casing of the totalizer 82. The totalizer shown in the present instance, as will be observed from these graduations 91, is arranged to add in dollars and cents of United 30 States money, with a blank space separating the tens of cents from the units of dollars.

In Fig. 3 the carriage is in the same position as in Fig. 6, namely, that which it occupies after the explanatory matter has been 35 written and the space key has been depressed and released. It will be noted in Fig. 3 that the totalizer is in position to add in tens of cents. As was said above, this is the position to which it is desired to bring the carriage in the vast majority of lines of writing in the special work for which the machine is designed. My improvement now to be described is designed to facilitate bringing the carriage to a point two steps to the right 40 of that shown in Fig. 3, so as to write units of dollars.

The ordinary equipment of the Remington No. 21 machine includes a carriage release key 92, consisting of a sheet metal lever 45 pivoted at 93 to the end bar of the truck 15 and having its forward end formed into a thumb or finger piece. This key or lever 92 is guided by means of a headed screw 94, passing loosely through a slot 95 in the lever and passing also through a washer 96 and 50 screwed into the bracket 85. A depending arm of the lever 92 is connected by a push link 97 with a bell crank 98 pivoted at 100 to the platen frame 16 and having a rearwardly extending arm 101. Said arm 101 55 lies underneath a bail rod 102 which passes through arms 103 to which it is rigidly secured by pins 104. The arms 103 are pivoted on the rod 44 at the back of the typewriter carriage. The construction is such that a depression of the release key 92 causes the rod 102 to swing upward about the rod 44 as an axis. The bar 68 which is mounted on the rack 33 has an ear 105 bent rearward therefrom, and overlying the rod 102 in such 60 fashion that an operation of the release key 92 will result in raising the rack 33 out of engagement with the pinion 32, as shown in Fig. 5; but when the rack 33 is released by the space bar 52 as shown in Fig. 4, it 65 does not operate the bail rod 102.

The rod 102 carries a stop 106 adapted, when said rod is moved upward as shown in Fig. 5, to strike a fixed stop 107 so as to arrest the leftward motion of the carriage. 70 This fixed stop 107 is here shown as consisting of a sheet metal bracket having a base flange that rests on the top plate 12, to which it is secured by screws 108, the upper part of the bracket arching forward over the rod 102, as shown in Fig. 3. The stop 106 may be any convenient sort of projection on the rod 102. In order to give it a suitable fine adjustment it is here shown in the form of a round nut, Fig. 7, threaded 75 on to a sleeve 110 which surrounds the rod 102, to which it is fixed by a pin 111. The stop 106 can be adjusted a short distance right and left by screwing it along the sleeve 110, spanner holes being shown for the purpose. There are also shown mounted on the sleeve 110 a washer 113 and lock nut 114, to 80 secure the adjustment, said lock nut being also shown with spanner holes.

In the normal position of the parts the 85 stop 106 can pass under the stop 107, as will be apparent from Figs. 1 and 4; but when the release key 92 is operated, as shown in Fig. 5, the stop 106 will strike the stop 107 and arrest the carriage. In the specific machine here shown, these stops are so located 90 as to arrest the carriage in the units of dollars position.

The paper or work sheet 115, a fragment 95 of which is indicated in Fig. 3, has for its first or left-hand column a date column 116 which is defined by an isolated tooth 117, Fig. 4, of the rack 33. When the carriage is drawn back to the right by the motor, this tooth 117 engages that interdental space of 100 130

the pinion 32 through which the center line 118 passes. As soon as the date is written the carriage takes a jump until it is arrested by the first of the continuous series of teeth 5 shown in Fig. 4. This brings the carriage to the position to write the first letter in the column 120 reserved for the name of the place that was called on the long distance telephone. This name, for example, Chicago, 10 is then written by striking the letter keys of the machine. When it is finished the operator depresses the space bar, as shown in Fig. 4 and releases it, thus bringing the carriage to the position shown in Figs. 3 and 15 6, whereupon the charge, in this instance 95¢, is written in column 121 and is added in the totalizer 82. It will be noted in Figs. 4 and 5 that the rack 34 has first two consecutive teeth and then three teeth are omitted, 20 a blank space being left, followed by other rack teeth. The construction is such that after writing the 95¢ in column 121, the carriage automatically jumps two spaces and into position to write a certain symbol, 25 such as "x" in column 122. In that step of the carriage following the writing of this symbol the margin stop 75 moves the arm 74 and sets the carriage return mechanism into operation. This draws the carriage 30 back to the right and line spaces the paper, whereupon the operations just described are repeated. It will be observed that all this takes place without the operator removing her fingers from the keyboard and in fact 35 with hardly a pause in her work. The bill is written line after line until all of the items have been entered, the carriage immediately returning to the right at the end of the last line. The operator is now ready 40 to copy the total of the charges out of the totalizer 82. If, as is ordinarily the case the amount of this total is equal to or more than one dollar, she then depresses the release key 92 and moves the carriage leftward 45 until arrested by the stops 106 and 107 and then releases the key. It will be seen from Fig. 5 that this allows the last tooth of the rack 33 to drop into the central interdental space of the pinion 32, this being 50 the position for units of dollars. The operator then writes the units of dollars, spaces across the decimal point by a stroke on the space bar and writes the cents of the total. Before writing the total, she strikes a subtract key, not shown, setting the adding mechanism to subtraction. The writing of 55 the total results in subtracting it from itself and from the totalizer, leaving the latter clear. 60 In case an occasional total should be as much as, or more than, ten dollars, the operator uses the release key 92 in the same manner as has been above described and then

strikes the back space key. This occurs infrequently, however, in this class of bills. 65

Various changes may be made in the details of construction and arrangements without departing from my invention.

What I claim as new and desire to secure by Letters Patent, is:—

1. In a typewriting machine, the combination with a carriage having a tendency to travel in letter feed direction, escapement mechanism therefor, and a plurality of feed rack sections the first of which can be released independently of the second, of two means for releasing said first rack section, one of said means allowing the carriage to run until arrested by the second rack section, and a stop connected with the other 80 said means and arranged to arrest the carriage short of the second rack section.

2. In a typewriting machine, the combination with a carriage having a tendency to travel in letter feed direction, escapement 85 mechanism therefor, and a plurality of feed rack sections the first of which can be released independently of the second, of a key and connections operating to release said first rack section and to allow the carriage 90 to run until arrested by the second rack section, a second key, a bar operated by said second key and having a carriage stop thereon, and a part connected with said first rack section and overlying said bar, whereby said 95 bar when operated releases said rack section.

3. In a typewriting machine, the combination with a carriage, escapement mechanism therefor, and a releasable feed rack, of a key, a bar on the carriage movable by said key, a stop on said bar, a fixed stop into the path of which said key moves the first mentioned stop, means whereby said bar may release said rack, and a key in the keyboard of the machine adapted to release said rack 105 independently of said stop bar.

4. The combination with a carriage and feed mechanism therefor including a releasable feed rack, of two flanges on said rack, a push rod acting on one of said flanges 110 to release the rack, a rod lying between the two flanges, and independent means for actuating said rod to cause it to act on the second flange to release the rack.

5. The combination with a carriage and feed mechanism therefor including a releasable rack and a letter-feed escapement, of two independent keys for releasing said rack, one only of said keys being connected to operate said escapement and a carriage stop controlled by the other said key. 115

Signed at the borough of Manhattan, city of New York, in the county of New York and State of New York, this 26th day of January, A. D. 1926.

FREDERICK A. HART.
